UNITED STATES PATENT OFFICE.

WILLIAM N. WINFIELD, OF DETROIT, MICHIGAN.

LETTER-HEAD.

1,267,034.

Specification of Letters Patent. Patented May 21, 1918.

Application filed November 20, 1916. Serial No. 132,307.

To all whom it may concern:

Be it known that I, WILLIAM N. WINFIELD, a citizen of the United States of America, residing at Detroit, in the county 5 of Wayne and State of Michigan, have invented certain new and useful Improvements in Letter-Heads, of which the following is a specification, reference being had therein to the accompanying drawings.

10 This invention relates to letter-heads and refers more particularly to a new and improved construction of letter-head or the like in which the sheet is folded from the side.

15 Among the objects of the invention are to provide a construction in which the sheet can be folded from the side and the address or other matter which is printed on one side of the sheet, can be read when the sheet is

20 either folded or unfolded; to provide a construction in which the cut-away portion is so arranged that there will be practically no loss in stock in manufacturing the letter-head and the latter can be cut from a rec-

25 tangular sheet; to provide a letter-head which can be readily cut from standard stock and economically manufactured; to so construct and arrange the sheet that if it is desired to use the same as a mailing card

30 the latter will have the same advantages as the letter-head while further utilizing as a sealing flap, a portion which is formed in the operation of cutting the letter-head from the rectangular blank; and in general to

35 provide a new and improved letter-head or the like.

In the drawings:

Figure 1 is a plan view showing the method of manufacturing the sheet;

40 Fig. 2 is a view of the letter-head in unfolded position;

Fig. 3 is an enlarged similar view showing the letter-head folded;

Fig. 4 is a view showing the sheet adapted 45 for use as a mailing card;

Fig. 5 is an enlarged sectional view of the construction shown in Fig. 4 when folded.

Describing in detail the sheet shown in

Figs. 1, 2 and 3, A designates the blank from 50 which the letter-head is cut. The blank is preferably of such size so that it can be severed into two letter-heads B and C. In manufacturing the blank it is however not cut on a straight line but one part is cut 55 along the line D and the other end along the line E, while the two lines of severation D and E are connected by an inclined line of severation F. To facilitate the cutting of the sheet the connection between the line 60 of severation F and the lines D and E are curved at G and H respectively.

Where the severed portions or sheets B and C are to be used as letter-heads the end J is preferably severed on the line K so that 65 the completed letter-head is of the form shown in Fig. 2. This permits the unfolded sheet to be lithographed or printed entirely on one side. The letter-head is then folded sidewise on the line L leaving exposed the name of the firm as indicated at M and a blank space N on the back of the sheet which when folded to the position shown in Fig. 3 forms the letter space for the sheet, while the name is also visible. 75 Thus with the novel construction above described the single printing or lithographing on one side can be used for carrying advertising matter or other information, while at the same time there is printed or litho- 80 graphed the name of the user, which name is visible both when the sheet is folded or unfolded.

Where it is desired to use the sheet as a mailing card, the construction remains 85 the same except the flap J is not removed but is gummed as shown in Fig. 4 and can be utilized for holding the card in its folded position, as shown in cross section in Fig. 5. In both cases the fold is made from the 90 side and the letter-head or mailing card can, if desired, be formed from a rectangular sheet.

What I claim as my invention is:

A letter-head, comprising a double width 95 blank which is arranged to fold sidewise and having on one side advertising matter and a heading arranged near the top of one

half above the advertising matter so as to be associated therewith in the unfolded position of the blank, the upper part of the other half of the blank being cut away to 5 also disclose the heading at the top of the sheet in the folded position of the blank, the part of the blank above which the head-

ing is disclosed in the folded position forming a letter writing space and the advertising matter being concealed in the folded 10 position of the blank.

In testimony whereof I affix my signature.

WILLIAM N. WINFIELD.
